11 Claims

ABSTRACT OF THE DISCLOSURE

The present switch is a visible blade type load break switch which is normally driven to open and closed positions, respectively, with a snap action by a dead-center spring mechanism operable by manipulation of an operating handle. The snap action mechanism is arranged so that in the event of failure of its springs it can be driven positively and directly by the handle to close the switch and to open the switch fully so that the blades are disposed outwardly beyond the arc stack of the switch.

The dead-center mechanism comprises two dead-center plates, juxtaposed face to face, which swing about offset parallel pivots, one plate being movable initially by the operating handle and, in turn, driving a pin for operating a blade-carrying cross bar, the pin, in turn, also driving the other plate. Dead-center springs are connected to the plates for driving them to fully open and close the switch, selectively, with a snap action when one of the plates has been moved by an operating handle beyond a predetermined position. The mechanism is so arranged that it provides a positive drive of the plates directly by the handle for effecting the positive drive of the blades to fully open or fully closed position, selectively, by the handle in event of the failure of the springs.

The movable blades are arranged so that they can be snapped into installed position in a movable cross bar and can readily be detached therefrom while the cross bar is installed in the housing. The cross bar itself is readily removable from the housing for replacement.

The switch mechanism is enclosed in an insulating housing which when supported on its supporting frame is in overlying, protecting and concealing relation to the mechanism.

The parts are devised so that the switch can be converted for right hand or left hand operation by simply repositioning the handle and dead-center plates.

The switch is adapted to be used unfused, or fused with various combinations of fuses of different lengths and diameters, as desired.

This invention relates to a load break switch adapted for use in control centers in fused or unfused condition. The switch employs rigid contact blades, as distinguished from contact shoes, which are mounted in a housing so they will be readily visible in the operating position of the switch. Various parts of the switch are so arranged that the switch can readily be converted to right hand or left hand merely by repositioning some of the parts.

An important object of the invention is to provide a switch employing a dead-center spring mechanism which is operable by an operating handle, and arranged so as to fully close and fully open the switch with a snap action in normal operation, and to be driven positively by the handle for moving the blades to fully open and fully closed position in the event of failure of the springs.

More specific advantages reside in the manner of mounting the blades in a molded cross-bar so that the blades can be readily installed or removed by snapping them into sockets therein without removing the cross-bar from

2

the switch, and further provide for ready removal of the cross-bar as a whole from the switch.

Another specific object is to overlie, protect and conceal the operating mechanism and snap acting mechanism by the blade supporting housing.

Various other specific objects and advantages of the invention will become apparent from the following description wherein reference is made to the drawing, in which:

10 FIG. 1 is a front elevation of a switch embodying the principles of the present invention, with a fuse plate attached;

FIG. 2 is a right side elevation, on a reduced scale, of the switch and fuse plate illustrated in FIG. 1;

15 FIG. 3 is a cross sectional view of the switch and is taken on the line 3—3 in FIG. 1, the fuse plate being omitted for clearness in illustration;

FIG. 4 is a bottom plan view of the switch illustrated in FIG. 1, the fuse plate being omitted;

20 FIG. 5 is an enlarged front elevation of the cross bar used in the switch for carrying the movable contact blades;

FIG. 6 is a bottom plan view of the cross bar illustrated in FIG. 5;

25 FIG. 7 is a vertical cross sectional view of the cross bar taken on the line 7—7 in FIG. 5;

FIG. 8 is a front elevation of the rear supporting frame of the switch with the cross bar operating mechanism mounted thereon, the switch and dead-center springs for the mechanism being omitted for clearness in illustration;

30 FIG. 9 is a bottom plan view of the structure illustrated in FIG. 8, part thereof being broken away for clearness in illustration; and

35 FIG. 10 is a fragmentary view similar to FIG. 8 showing the driving plates of the cross bar operating mechanism and dead-center springs thereof in one operating position, the position of the plates in the other operating position being indicated in dot and dash lines.

40 Referring to FIGS. 1 and 2, the switch comprises a main housing or body 1 of rigid insulating material, such as hard rubber, phenolic, or the like preferably molded in one piece. The body is mounted on a metal supporting frame in the form of a rear plate 2 having lateral forwardly extending walls 3 which are disposed along the side walls of the body, respectively, and spaced outwardly therefrom, as best illustrated in FIGS. 1, 2 and 8, over the major portion of their facial extent.

45 The body is open at the front and is provided with channels 4 which are open downwardly and at their forward ends. Stationary contacts 5 are mounted in the channels, respectively, and are adapted to receive the movable contact blades 6 which are carried on a cross bar 7 of rigid insulating material. Suitable forward barrier walls 8 are provided around the front entrances to the channels 4 and arc stacks 9 are provided within the channels rearwardly from the barrier walls 8.

50 Each of the stationary contacts 5 is in the form of a forwardly open yoke between the arms of which the associated movable contact is driven and removed by rocking of the cross bar 7. Each of the contacts 5 is connected to a line terminal 10 which, at its upper end, is adapted to be connected by a screw 11 to an external conductor. The line terminal 10 is suitably secured in the body 1 by terminal screws 12.

55 The cross bar 7 is provided at its ends with trunnions 14 and is held in position within the body 1 by engagement of the trunnions 14 within suitable bearing apertures 15 in the side walls 3, respectively, of the frame 2. Rocking of the cross bar about its axis, in the clockwise direction in FIG. 3, makes contact between the movable con-

tact blades 6 and associated contacts 5. Each contact blade 6 is connected by a flexible conductor 16 to a load terminal 18 secured in the body 1 and provided with a connector 19 for connecting an external conductor thereto. The flexible conductor 16 is brazed or soldered at its opposite ends to an associated blade 6 and load terminal 18, respectively.

Alternatively, in a manner later to be described, the contact blades 6 may be connected by the flexible conductor 16 directly to a fuse plate without use of the load terminals 18 and connectors 19.

It is desirable that the blades be readily connectable to, and disconnectable from, the cross bar 7. For this purpose, the bar is provided with a plurality of sockets 20 arranged in a row along the bar and extending generally radially of the axis thereof. For providing a snap fastening connection between each blade 6 and the bar 7, each blade is provided with a notch 22 and the bar, at each socket, is provided with a shoulder 24. A snap fastener 25 in the form of a strip of spring steel has one J-shaped end 26 which can be snapped into the notch 22 and, extending from the end 26, an arm portion 28 which engages the shoulder 24. The blade has a part of its forward edge offset rearwardly of the blade, as at 29, for accommodating the portion 28 of the snap fastener 25 during the insertion of the blade lower end foremost into the socket 20 with the snap fastener 25 installed therein. When the upper end of the portion 28 reaches the shoulder 24, it springs forwardly and bears endwise of the spring thereagainst to prevent displacement of the blade 6. The cross bar has forwardly open slits 30, arranged one for each socket through which the blade of a screwdriver may be inserted into the associated socket. If it is desired to change blades for any reason, the screwdriver blade can be passed through the slit 30 and caused to engage with the portion 28 of the snap fastener and push it back into the clearance space provided by the offset 29 so that the end of the portion 28 is disengaged from the shoulder 24 so as to permit the blade with the snap fastener attached to be withdrawn from the socket.

It is necessary to rock the cross bar for moving the blades 6 with a snap action to contact-making position and to open position. Further, it is necessary that in the open position the outer or free end of each blade 6 be disposed outwardly from its associated channel beyond the arc stack and within the confines of the barrier walls 8.

In order to assure these movements, a snap action mechanism, indicated generally at 31, is provided. In the switch shown for purposes of illustration, the snap action mechanism 31 is mounted on the metal plate 2 of the metal frame so that it is concealed behind the rear of the body 1 and protected thereby during normal operation. Since a snap action for both making and breaking contact is desired, two dead-center plates 34 and 35 are provided. For mounting the plates in operating position, the plates are disposed in face to face juxtaposition with operating clearance and are supported in this position on the plate 2. For this purpose, laterally offset bosses 36 and 38, facing forwardly from the plate 2, are provided. The plates are arranged with plate 34 juxtaposed against the bosses and the plate 35 disposed forwardly thereof. The plate 34 is pivotally connected to the boss 36 by a pivot 39. The plate 35 is connected to the boss 38 by a pivot 40. Each plate can swing about the axis of its associated pivot independently of the other plate. The plate 34 has a slot 41 which is of constant radius and curvilinear about the axis of the pivot 39. Correspondingly, the plate 35 has a slot 42 of constant radius and curvilinear about the axis of the pivot 40. The pivot 39 extends through the slot 42 and has an enlarged head 39a which helps to hold the plates in juxtaposition. Correspondingly, the pivot 40 extends through the slot 41, and has an enlarged head 40a for a like purpose. The slot of each plate is such that the pivot of the opposite plate

can slide therein endwise of the slot as each plate swings about its pivot relative to the other plate.

In order to operate the switch, one of the plates, for example, the plate 35, is provided at the end opposite to pivot 40 with a plurality of radial teeth or fingers 44. Mounted on a suitable pivot pin 45 and extending inwardly from one of the side walls 3 is an operating lever 46 which is disposed in the clearance space between the wall 3 and adjacent side of the body. At its outer end the lever 46 carries spaced fingers or teeth 46a which, as the lever is rocked about its axis, can mesh in the manner of a gear with the fingers 44 to swing the plate 35 to and fro about its axis. The lever 46 is provided with means for rocking it about its axis sufficiently to move the blades 6, through the medium of the plates 34 and 35 and connection with the cross bar 7, to fully open and closed positions.

If overload release devices are to be used with the switch, then such device may be connected by a suitable link to the lever 46. However, in the form illustrated, the lever 46 is provided with a handle 47 for manual operation.

The plates 34 and 35 are so connected to each other that when the plate 35 is swung clockwise about its pivot 40 by operation of the lever 46, it drives the plate 34 in a counterclockwise direction about the pivot 39. When the plate 35 is swung counterclockwise by the handle 46 it drives the plate 34 clockwise. For effecting this driving relation, the plate 35 is provided with a downwardly projecting finger or boss 48 which may be formed by depressing a portion of the metal of the plate 35. The boss is disposed in a slot 49 in the plate 34. The slot is so arranged that upon swinging of the plate 35 clockwise and counterclockwise, respectively, the boss 48 can engage the opposite ends or shoulders of the slot 49, respectively, and thereby positively drive the plate 34 by the plate 35 to the fully rocked positions of the plate 34. The length of the slot 49 is such that the boss 48 does not engage the ends of the slots under normal driving of the plate 34 by the plate 35 through the medium of dead center snap action springs, later to be described.

In order to drive the cross bar 7 in response to operation of the lever 46 and plates 34 and 35, a cross bar pin 50 is provided. For connecting the pin 50 to the cross bar, the cross bar 7, as best illustrated in FIGS. 6 and 7, has a plurality of sockets 51 spaced apart from each other axially of the cross bar. In the form illustrated, two sockets 51 are provided so that the mechanism herein described can be reversed for right and left-hand operation and the pin can be made to associate with the proper slot in the reversed position of the operating mechanism. For this selective right or left-hand arrangement each of the side walls 3 is provided with a pivot pin 45 such as hereinbefore described. Since the plates 34 and 35 are symmetrical, instead of placing the operating handle 46 at the right, as in FIG. 8, it may be installed on the left hand pivot 45 and the plates 34 and 35 rotated at 180° about an axis parallel to the axes of the pivots 39 and 40 and reinstalled on the plate 2 in the new position. In one position of the handle the plates, the cross bar pin 50 is disposed in one of the sockets 51 and in the opposite position of the handle and plates it is disposed in the other of the sockets 51. The cross bar pin 50 has a hooked end portion 50a which, as indicated in FIG. 3, is disposed in the selected one of the sockets 51, and has a straight end portion 50b extending therefrom which is connected to the plates 34 so as to be driven thereby.

If preferred, the cross bar pin 50 may be formed without the hooked end 50a so as to have two straight end portions and may be connected to the cross bar 7 by one of a plurality of angularly disposed drilled holes.

To effect the driving connection with the pin, the plate 34 is provided with an aperture 52 into which the

straight end 50b of the pin 50 fits with operating clearance. The plate 35 is provided with a passage 54 which overlies the aperture 52 in the plate 34 and is of such size as to prevent driving of the pin by the top plate 35 during initial driving of the top plate 35 by the handle in the switch opening direction to dead-center position. When the top plate 35 passes slightly beyond dead-center position in the opening direction, the bottom plate is slightly past dead-center and snaps in the opening direction and drives the pin 50 with a snap action to open the switch with a snap action.

Upon movement of the top plate in the closing direction, the pin 50 is engaged at once by the opposite end wall of the slot of the top plate and moved partway in the switch closing direction. As the plates pass dead-center position of the bottom plate 34, the bottom plate snaps in the switch closing direction and, by engagement of an end of its slot with the pin 50, drives the pin with a snap action to close the switch with a snap action.

The plates are arranged so that when the top plate 35 is moved a slight distance beyond a dead-center position relative to the pivotal axes of the plates, they can be operated by dead-center springs to open or close the switch with a snap action. For this purpose, the plate 34 is provided with a post 56 and plate 35 is provided with a post 58. Mounted on the post 56 for rocking movement about an upright axis is a spring holder 59. The spring holders 59 and 60 are provided with apertures 61 and 62, respectively, which apertures are equally spaced from their respective posts. A pair of dead-center springs 64 and 65 are provided, the opposite ends of the spring 64 being connected in one aperture 61 of the spring holder 59 and the corresponding aperture 62 of the spring holder 60. Correspondingly, the dead-center spring 65 is connected to the opposite aperture 61 of the spring holder 59 and opposite aperture 62 of the spring holder 60. The axes of the posts 56 and 58 are such with respect to the plates 34 and 35 and the dead-center springs that when the plate 35 is moved in either direction slightly beyond a dead-center position in which the posts 56 and 58 are aligned, parallel to the axes of the springs, the springs will become operative and move the plates with a snap action relative to each other further in the direction in which the plate 35 was moved in passing dead center. Thus both plates are moved in a snap action. This snap action occurs before the boss 48 engages either end wall of the slot 49, and hence the boss 48 and end walls of the slot 49 are inoperative so long as the dead center springs 64 and 65 are operative. However, the slot and boss provide a lost motion positive drive between the plates. The lost motion is such that, though the boss 48 and ends of the slot 49 do not interfere with the normal movement of the plates by the snap action of the dead center springs, in event the springs become broken or fail to function, the lost motion can be taken up by movement of the plate 35 by the handle 46. The slot 49 and boss 48 are so related that upon driving the plate 35 to its final position in either direction by the handle 46, the plate 35 drives the plate 34 to the final position to which the plate 34 would have been driven by the dead-center springs had they remained effective. This lost motion positive drive for opening and closing the switch in combination with a dead-center spring mechanism has the distinct advantage in that failure of the snap action mechanism does not prevent manual and positive operation of the switch.

It is desirable in many instances to provide a fuse plate which can accommodate fuses of different diameters and lengths. For this purpose, a fuse plate, as illustrated in FIGS. 1 and 2, is provided. The fuse plate 70 comprises a body of rigid insulating material which is secured by screws 71 to the body 1. For supporting the plate 70 in an upright position suitable stay braces 72 are connected at the lower end to the plate 70 and at the upper end to the plate 2. The plate 70 carries a 75

plurality of line terminals 74 arranged in a row extending across the upper end of the plate and complementary load terminals 75 spaced directly therebeneath, respectively. The upper terminals 74 may be connected to the terminals 18 heretofore described, respectively. However, when the fuse plate is to be used, the terminals 18 are unnecessary, and the flexible conductors 16 may be connected directly to the line terminals 74, respectively, at one end and to the blades 6 at the opposite end in any conventional manner.

Suitable means are provided, as indicated at 76, for connecting the load terminal 75 to external conductors. In order to hold selected types of fuses, each of the line terminals 74 is provided with a plurality of tapped apertures 77 arranged in an upright row in suitably spaced relation to each other. Each load terminal 75 is provided with tapped apertures 78 arranged in an upright row in alignment with the row of apertures 77. Fuse clips 79 and 80 are provided for engaging opposite ends of a cylindrical fuse. For example, the clips 79 are adapted to engage the upper end of the fuse and the clips 80 are provided with a bottom wall and are adapted to engage the lower end of the fuse. Each clip 79 is connected to a line terminal by a suitable screw engaged in a selected one of the apertures 77 and each clip 80 is connected to a corresponding load terminal by a suitable screw engaged in a selected one of the apertures 78. The particular apertures at which the fuse clips are connected are selected in accordance with the length of the fuse to be accommodated. The clips themselves are selected in accordance with fuse diameter.

Thus, by shifting the selected fuse clips to different apertures, or using fuse clips of different sizes, substantially any make of fuse suitable for use with this type and capacity of equipment can be accommodated.

Having thus described my invention, I claim:

1. In a switch, a support; a set of stationary contacts carried thereby; a movable cross bar; means connecting the bar to the support for movement in opposite directions, selectively; complementary movable contacts carried by the cross bar and movable thereby to contact making position and to contact opening position, selectively, upon movement of the bar in said directions, respectively; a pair of members; parallel laterally offset pivots connecting the members, respectively, to the support and supporting them in face to face overlapping relation, one member in front of the other with each member extending from its pivot generally endwise toward the pivot of the other member, each for swinging in opposite directions, selectively, along an arcuate path about the axis of its associated path;

drive means for driving the front member along its path in said opposite directions, selectively; lost motion connecting means drivingly connecting the front member to the rear member so that the front member is movable from either end of its path partway toward the other end of its path, in the selected one of its directions of movement therealong, independently of the rear member, to a dead center position, and so that the front member drives the rear member positively entirely to said other end of the path of the rear member upon continued movement of the front member, in said selected direction, beyond said dead center position while permitting continued movement of the rear member entirely to said other end of its path in the selected direction, independently of the front member;

dead center spring means drivingly interconnecting the members and rendered operative, by moving the front member beyond said dead center position toward said other end of its path in the selected direc-

tion of movement, to drive the rear member with a snap action to its said other end of its path, and means connecting the rear member to the cross bar for driving the cross bar in one of its directions of movement to contact opening position upon movement of the rear member to one end of its path and to contact closing position upon movement of the rear member to the other end of its path.

2. The structure according to claim 1 wherein said lost motion connecting means comprises a pair of shoulders on one member spaced apart from each other along its path;

shoulder means on said other member disposed between said shoulders and spaced from each of them a distance such that the shoulder means are disengaged from both of said shoulders during movement of the front member away from either end of its path to a position beyond dead center position, and engage the shoulder toward which the shoulder means is moving upon continued movement of the front member in the same direction.

3. The structure according to claim 1 wherein one member has a slot therein offset from its pivot; the ends of the slot are the shoulders;

a finger is provided on the front plate and extends into the slot; and the shoulder means are the opposite sides of the fingers facing towards the opposite ends of the slots, respectively.

4. The structure according to claim 1 wherein each member has a passage therein elongated endwise of its path;

the pivot of each member extends through the passage of the other member with operating clearance; and the point of connection of the dead center spring means with each member is on the opposite side of the passage of the member from the pivot of that member.

5. The structure according to claim 1 wherein the means connecting the rear member to the cross bar is a rigid rod connected at one end to the cross bar at a location in front of the front member and having its other end received in a slot in the rear member and extending through a passage in the front member with such clearance that the trailing end of the slot in the direction of movement of the front member, in either selected one of said directions, engages the rod after movement of the front member partway toward dead center position and thereby initiates swinging of the rear member in the selected direction prior to the dead center spring means becoming operative.

6. The structure according to claim 5 wherein said members are plates, respectively, and are in face to face juxtaposition.

7. The structure according to claim 1 wherein said cross bar has a plurality of sockets therein, each with an open end in the peripheral wall of the cross bar;

each movable contact includes a body portion with a contact at one end and a shoulder spaced from the contact toward the opposite end;

said bodies are received in the sockets through the open ends thereof, respectively, said opposite ends foremost;

said shoulders of the bodies face toward the open ends of the sockets, respectively;

each socket has a shoulder therein facing away from its open end;

resilient snap fasteners are provided for the bodies, respectively;

each snap fastener has a shoulder portion detachably engaged with the shoulder of its associated body and another shoulder detachably engaged with the shoulder of its associated socket when the snap fastener is in a fastening position;

passage means are provided in the cross bar and communicate with the sockets, respectively, and afford

access to the snap fasteners in the sockets by a tool so that each snap fastener can be individually strained transversely of its associated socket to a releasing position wherein its said other shoulder is offset from the complementary shoulder of its associated socket; and each body has a concavity which can accommodate a part of its associated snap fastener in said released position so that the body and its associated snap fastener can be withdrawn endwise as a unit from the associated socket.

8. In a switch, a set of stationary contacts; a movable cross bar of insulating material; means supporting the cross bar for movement in opposite directions, selectively;

complementary movable contacts carried by the cross bar and movable thereby to contact making position and contact opening position, selectively, upon movement of said bar in said direction, respectively; said bar having a plurality of sockets therein, each with an open end in the peripheral wall of the cross bar; each movable contact including a body portion with a contact at one end and a shoulder spaced from the contact toward the opposite end; characterized in that:

said bodies are insertable in the sockets through the open ends thereof, respectively, said opposite ends foremost;

said shoulders of the bodies face toward the open ends of the sockets, respectively;

each socket has a shoulder therein facing away from its open end;

resilient snap fasteners are provided for the bodies, respectively;

each snap fastener has a shoulder portion detachably engaged with the shoulder of its associated body and another shoulder detachably engaged with the shoulder of its associated socket when the snap fastener is in a fastening position;

passage means are provided in the cross bar and communicate with the sockets, respectively, and afford access to the snap fasteners in the sockets by a tool so that each snap fastener can be individually strained transversely of its associated socket to a releasing position wherein its said other shoulder is offset from the complementary shoulder of its associated socket; and each body has a concavity which can accommodate its associated snap fastener in said released position so that the body and its associated snap fastener can be withdrawn endwise as a unit from its associated socket.

9. The structure according to claim 8 wherein each body has a notch opening laterally of the cross bar with one side wall of the notch facing the open end of the socket and providing the shoulder of the body; each snap fastener is a leaf spring having an end portion fitted within the notch and bearing against said side wall and having another portion extending outwardly of the notch and toward the outer end of the body;

said spring has a shoulder facing toward the bottom of the socket and engaging the shoulder of the body when the leaf spring is in stressed flexed position;

the concavity of the body faces the leaf spring and accommodates a portion of the leaf spring when the leaf spring is stressed toward the body a predetermined distance such that the shoulder of the leaf spring is offset from the shoulder in the socket, whereby the body with the leaf spring can be removed through the open end of the socket while the spring is held in stressed condition by the tool.

10. The structure according to claim 8 wherein said movable contacts are switch blades and are detachably received in the sockets, respectively, in the cross bar; the snap action fasteners detachably engage the inner

end portions, respectively, of the blades and the cross bar and thereby connect the blades to the cross bar;
a housing encloses the switch;
said blades have outer end portions which extend outwardly beyond the cross bar and are positioned for access by a tool for withdrawal of each blade from its associated cross bar socket at the front of the housing when the cross bar is in the open contact position and the snap fastener of the particular blade is released.

11. The structure according to claim 1 wherein supports for the drive means are mounted on the base at opposite ends of the pair of members, respectively;

the drive means include a drive member connectable to 15 said supports, selectively, and which, when so connected, is movable in opposite directions, selectively, along predetermined paths, respectively;
the drive member is arranged so that when it is connected to one of said supports and said pair of members is in a first mounted position on the base, the drive member is detachably drivingly connected to said front member; and when the drive member is connected to the other of said supports and said pair 20 of members is in a second mounted position on the 25

base in which the pair is rotated as a unit about an axis parallel to, and midway between, the axes of said pivots while maintained parallel to its first mounted position, the drive member is detachably drivingly connected to said front member in the same driving relation; and

the means connecting the rear member to the cross bar is detachably connectable to the cross bar in two selective positions corresponding, respectively, to the two mounted positions of the pair of members.
